KNIFE

Edward B. Smith, Jr., Arlington Heights, Ill., assignor to American Home Products Corporation, New York,
N.Y., a corporation of Delaware

Filed June 7, 1967, Ser. No. 7,385

Term of patent 14 years

(Cl. D95—3)

FIG. 1 is a side elevational view of a knife.

FIG. 2 is an edge view thereof.

FIG. 3 is an enlarged section taken along line 3—3 of FIG. 1.

FIG. 4 is an enlarged fragmentary section taken along line 4—4 of FIG. 1.

The essential features of my design reside in the parts shown in full lines.

I claim:

The ornamental design for a knife, as shown and described.
